UNITED STATES PATENT OFFICE.

ROBERT ALEXANDER MILLER-ARGUE, OF ESSENDON, MELBOURNE, VICTORIA,
AUSTRALIA.

APPARATUS FOR CRANKING OR STARTING INTERNAL-COMBUSTION ENGINES.

1,396,647.

Specification of Letters Patent. Patented Nov. 8, 1921.

Application filed July 12, 1920. Serial No. 395,647.

To all whom it may concern:

Be it known that I, ROBERT ALEXANDER MILLER-ARGUE, a subject of the King of Great Britain and Ireland, and a resident of 5 the postal district of Ascot Vale, in the city of Essendon, a suburb of the city of Melbourne, in the county of Bourke, State of Victoria, Commonwealth of Australia, (whose post-office address is 257^A Ascot Vale 10 road, in the said postal district of Ascot Vale,) have invented a certain new and useful Improved Apparatus for Cranking or Starting Internal-Combustion Engines, of which the following is a specification.

15 This invention relates to apparatus for initially turning the crank shaft of an internal combustion engine to start the same and its object is to provide a simple, inexpensive and effective apparatus particularly 20 adapted for use with the engines of motor vehicles, but also applicable to other internal combustion engines, whereby the engine may be quickly and easily started without excessive effort by the operator.

25 The invention is devoid of electrical and complicated mechanical parts, is not liable to derangement and may be easily applied to existing as well as to new engines. Furthermore, if for any reason it should be 30 necessary or desirable to use the ordinary crank handle in starting this may be done without interference with the parts of the invention. The features of novelty are pointed out in the appended claims.

35 Referring to the drawings which form part of this specification:—

Fig. 1 is a view of a pin or stud wheel.

Fig. 2 is a rear view of a catch wheel.

Fig. 3 is a detail view showing a cushion 40 carried by the limit stop of a catch block.

Fig. 4 is a detail view showing a modified catch block provided with a roller and a fixed catch.

Fig. 5 is a detail view showing a hinged 45 catch.

Fig. 6 is a view looking at the front or opposite side of the catch wheel seen in Fig. 2 and showing also the pin or stud wheel one of the pins of which is engaged by the 50 catch of the catch wheel which has been partially rotated by the pull line.

Fig. 7 is a plan of Fig. 6.

Fig. 8 is a section taken on line A—A of Fig. 2, the pin wheel being omitted.

Fig. 9 is a perspective view of the catch 55 block.

Fig. 10 is a sectional detail view showing the means of attaching the pull line to the rim of the catch wheel.

According to the invention there is secured to the crank shaft 2 or an extension thereof an element comprising a pin or stud wheel consisting of a central boss 3 and a rim 4 united by a series of rotating spokes 5. These spokes may, if desired, be suitably inclined to act as a fan for cooling the engine.

Projecting from one side of the pin wheel, near its outer periphery, are a series of pins or studs 6 of any suitable number and spaced 70 at equal distances apart around the wheel.

Carried by the frame of the engine or the chassis 7 of the motor vehicle is a stationary central sleeve 8 around the periphery of which are ball bearings 9. The crank shaft 75 2 passes through the sleeve 8. The sleeve 8 is provided with shoulders 10 by which it is locked against rotation on the chassis 7. The sleeve is further provided with an enlarged collar 12 provided with stud or 80 screw holes 11 to accommodate screws by which the sleeve 8 is secured to the chassis 7. Formed in one end of the sleeve 8 is a plurality of spring adjusting recesses indicated at 13. Secured to the sleeve 8 and 85 closing the recesses 13 is a holding ring 14 retained by screws 15 or the like.

Mounted upon the sleeve 8 is a manually rotated element comprising a catch wheel 90 having a boss 16. Radiating from the boss 16 is a series of spokes 17 carrying at their outer ends a rim 18. Formed in the outer surface of the rim 18 is a circumferential groove indicated at 19. The rim of the catch wheel does not form a complete circle 95 but has a section removed forming a gap, indicated at 20, between its two ends. Formed through the rim 18 at any convenient point is a pull line hole indicated at 21. The said hole passes through the rim 100 18 and through one of the spokes 17, as shown in Fig. 6. Carried by the spoke through which the hole 21 passes is a retaining plate 22 secured by screws or the like.

Carried by one of the spokes 17 of the catch wheel is a hinge pin 23 to which is pivoted one end of a catch block 24. Carried by the catch block 24 and adapted to engage the spoke 17 carrying the hinge pin 23, is a limit stop 25. The outer or free end of the catch block 24 carries a catch 26 which may be integral with the catch block or hinged to a hinge pin 27 carried thereby, as seen in Fig. 5. The catch 26 is provided with a straight or substantially radial inner face 28 and a curved or inclined outer face 29. Or, as shown in Fig. 4, a roller 30 may be provided in lieu of the outer face 29.

The catch block 24 is also provided at one side with an inclined pathway 31 the inner end of which is provided with a recess 32 to accommodate a lifting roller hereinafter described. Adjoining the recess 32 and at the extreme inner end of the inclined pathway 31 is a limit stop 33. This may be provided with a rubber cushion 34 or the like as seen in Fig. 3.

The catch block 24 is normally held inward by a radially disposed spring 35 which is attached at one end to the catch block or a boss thereof and at its other end to the boss 16 of the catch wheel.

The catch wheel is also provided with a return spring 36. The spring 36 is preferably of a helical nature and coiled within the stationary sleeve 8. Its first end 37 is accommodated in one of the spring adjusting recesses 13 and retained therein by the holding ring 14. Its second end 38 passes through a lug 39 carried by a cross piece 40. The cross piece 40 is provided with a free axle hole and is secured to the catch wheel by screws 41 or the like.

Passing through the pull line hole 21 in the rim 18 of the catch wheel and secured by the retaining plate 22 is the first end 42 of a pull line 43. The pull line passes around the groove 19 of the rim 18 of the catch wheel and may then be led off by suitable guides and pulleys to the dashboard of a motor vehicle or to any other convenient point. It is provided with a suitable handle or the like.

The stationary sleeve 8 is provided with an extension or arm 44 carrying a pin or axle 45. Mounted on this axle is a catch lifting roller 46.

In operation a tug on the pull line 43 causes the catch wheel to be partially rotated thereby causing the inner face 28 of the catch 26 to engage one of the outstanding pins 6 of the pin or stud wheel. The pin wheel being fixed to the crank shaft or an extension thereof causes the shaft to be turned and the engine started. As the pin wheel rotates with the crank shaft the outstanding pins 6 successively engage the curved outer face 29 of the catch wheel and lift the catch block 24 which thus allows the

pins 6 to pass. This operation continues until the return spring 36 has brought the catch wheel back almost to its original position after the release of the pull line. The roller 46 on the arm 44 now engages the inclined pathway 31 of the catch block 24 thereby causing the catch 26 to be lifted out of the path of the pins 6 of the rotating pin wheel.

The cushion 34 absorbs the shock when the limit stop 33 strikes the roller 46. The engagement of the pins 6 with the curved outer face 29 of the catch 26 when the catch wheel is returning to its initial position also reduces the impact. It will be seen that the roller 46 rests within the recess 32 of the inclined pathway 31 of the catch block 24. The limit stop 25 prevents the catch block 24 falling beyond a predetermined distance under the influence of the spring 35 when the catch wheel is rotated by the pull line 43. With the helical spring 36 arranged as shown in the drawings it is practically impossible to overstrain the spring by an excessive pull upon the pull line as the spring coils are of sufficient diameter and are sufficiently spaced as to allow for necessary strain.

In the case of a back fire the pin wheel which is engaged with the inner face 28 and the catch 26 cannot pass the latter. The catch wheel is then turned in the reverse direction until the inclined pathway 31 of the catch block 24 engages the lifting roller 46 and causes the catch to be lifted out of the path of the pins 6.

Having now described my invention what I claim as new and desire to secure by Letters Patent is:—

1. An improved apparatus for starting internal combustion engines, comprising a stud wheel secured to the crank shaft and having a plurality of outstanding studs, a stationary sleeve, a catch wheel mounted upon the sleeve and having a circumferential groove, a pull line secured at one end to the catch wheel and passing around the groove, a catch block carried by the catch wheel, a lifting roller engaged by the catch block, a helical spring disposed within the stationary sleeve, and means for adjusting the spring.

2. A starting device for internal combustion engines, comprising a stud wheel secured to the crank shaft having a plurality of laterally projecting studs thereon, a stationary sleeve secured to the engine frame, a catch wheel rotatable on the sleeve and having a circumferential groove, a pull line secured at one end to the catch wheel and passing around the groove, a catch block carried by the catch wheel, said block being pivoted at one end to the catch wheel and formed with a catch at the other end adapted to engage the studs on the stud wheel,

means for lifting the catch block out of engagement with the studs, and resilient means engaging the stationary sleeve and the catch wheel for normally holding said catch wheel in one position.

3. A starting device for internal combustion engines, comprising a stud wheel secured to the crank shaft having a plurality of laterally projecting studs thereon, a stationary sleeve secured to the engine frame, a catch wheel rotatable on the sleeve and having a circumferential groove, a pull line having one end secured to the catch wheel

and passing around the groove, a catch block carried by the catch wheel, said catch block being pivotally connected to the catch wheel at one end and formed with a roller receiving recess, a cam face, and a catch, and a roller carried by the stationary sleeve, whereby in one position, the catch block will be held in inoperative position when the roller is seated in the roller receiving recess.

In testimony whereof I affix my signature.
R. A. MILLER-ARGUE.

Witness:

CECIL McPLESTED.
